UNITED STATES PATENT OFFICE.

LUCIUS E. WHITON, OF WEST STAFFORD, CONNECTICUT.

COPYING-BOOK.

SPECIFICATION forming part of Letters Patent No. 354,959, dated December 28, 1886.

Application filed February 12, 1886. Serial No. 191,740. (No model.)

To all whom it may concern:

Be it known that I, LUCIUS E. WHITON, of West Stafford, in the county of Tolland and State of Connecticut, have invented a new and 5 useful Improvement in Copying-Books; and I do hereby declare that the following is a full, clear, and exact description of the same.

My invention relates to letter-press-copying books shown in an application filed by me in 10 the United States Patent Office on the 14th day of November, 1885, and numbered 182,798. The book described in said application is formed of thin leaves of paper adapted to letter-press copying and divided into sections by 15 leaves of thicker paper having exposed marginal letters. The thick paper leaves are shown as made with a part of the margin cut away in the usual manner of indexing by marginal letters. It was suggested in said application 20 that the divisions could be separately supplied, in order that if any one division became exhausted another could be inserted. I have devised means of supplying these divisions or signatures as an article of manufacture, adapted 25 to be put together in a temporary binder in place of those exhausted, or to form an entire book, the divisions or signatures being adapted to be inserted in any position in the letter-index.

30 To this end my invention consists of a division or signature composed of leaves of ordinary letter-press-copying paper with a projecting or division cover of stouter paper on one or both sides of the division or signature, 35 the leaf or one of the leaves having its margin extended beyond the edges of the letter-press-copying leaves and provided with the letters of the alphabet arranged vertically on its exposed margin.

40 The accompanying drawings show such a signature in perspective in Figure 1. Fig. 2 is a cross-section.

In the drawings I have shown only one cover or division-leaf, A, this being on the back of 45 the signature. The signature or division of letter-press leaves is shown at B. In this figure the marginal extension of the cover A is shown at c. This cover may be made of Manila or any other suitable paper. The letter-

press-copying leaves are attached to it by sewing or otherwise, and a strong strip of cloth, a, may also be applied to the edges of the leaves where they are bound to the cover. The cover of stout paper is represented as extended out beyond the edges, as shown at D, and this 55 is punched with holes, as shown at b, for temporary binding. If necessary or advisable, the cover or divisional leaf may be made flexible on the line e. On the exposed margin c, I place the letters of the alphabet in their order. All of the signatures being made, in this way, they are all fitted for any position in the book, and when the signature is to be placed that part of the margin containing the letters of the alphabet is removed from the bottom up 60 to the letter which is to form the index-letter of the division. All of the remaining letters of the margin will be covered by the uncut portions of the margins of the preceding signatures or divisions. It will be understood 65 that these divisions are formed with the entire alphabet on the exposed margins, and are to be cut and fitted by the user, all being alike applicable to fit any place in the alphabet from A to Z. 75

I claim as my invention—

1. A signature for letter-press-copying books, composed of ordinary letter-press-copying paper and a cover having an exposed margin with the letters of the alphabet placed 80 thereon in their order, substantially as described.

2. A signature for letter-press-copying books, composed of ordinary letter-press-copying paper and a cover or divisional leaf of 85 heavier paper having on one side an exposed margin with the letters of the alphabet placed thereon in their order and on the other side a margin exposed beyond the letter-press-copying paper with perforations for temporary 90 binder.

In testimony whereof I have signed my name to this specification in the presence of two subscribing witnesses.

LUCIUS E. WHITON.
